FILM DRIER

Francis C. Frey, Los Angeles, Calif.

Application October 15, 1940, Serial No. 361,246

2 Claims. (Cl. 34—122)

This invention relates to apparatus for drying photographic film.

It is well-known that after development, the emulsion on a film retains considerable moisture. To dry such film it has been customary to hang it on a support; but such a process may require as much as ten or twelve hours, with attendant danger of warping or curling.

By the aid of the present invention, the period required for drying may be greatly reduced and yet this is accomplished by simple, inexpensive apparatus.

In carrying out this object, use is made of a stream of heated air. Accordingly it is one of the objects of this invention to provide a practical and inexpensive drier for photographic films, operating by virtue of a stream of heated air.

It is another object of this invention to provide such apparatus which will dry the film uniformly.

It is another object of this invention to provide such apparatus which will maintain the film against curling during drying.

It is still another object of the invention to provide a film drier which is adapted for use with either roll film or cut film.

It is a still further object of the invention to provide a film drier which is simple and inexpensive to manufacture, and may be readily knocked down to occupy less space, as for shipping, or packing.

This invention possesses many other advantages, and has other objects which may be made more easily apparent from a consideration of several embodiments of the invention. For this purpose there are shown a few forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

In the drawings:

Figure 1 is a pictorial view of the film drier;

Fig. 2 is a transverse section through the drier;

Fig. 3 is a view, partly in elevation, and partly in section as seen on plane 3—3 of Fig. 2;

Fig. 4 is a cross section on an enlarged scale, as on plane 4—4 of Fig. 3, part of the figure being broken away to reduce its size;

Fig. 5 is a fragmentary cross section on an enlarged scale as seen on plane 5—5 of Fig. 2;

Fig. 6 is an end elevation of an alternative form of reel which may be used with the drier; and

Fig. 7 is a side elevation of the reel of Fig. 6.

Referring to the drawings and particularly to Figs. 1, 2 and 3, the drier comprises a reel or cage or drum 1 having longitudinal bars 2 which are intended to carry the film 71 to be dried. This film, which may be of any length, may be attached at each end to the appropriate bars 2, as by the spring clips 72, and rubber bands passed around the bar and hooked on hooks 73 of the clips 72. The drum or reel may of course carry as many lengths of film 71 as may be accommodated by the periphery of the drum. The emulsion side of the film is of course directed outwardly.

The reel or drum 1 is rotatably supported by upright members 3, 4 which are disposed on opposite sides of a box or housing 5, forming the base of the drier. As will be hereinafter described, the drum is rotated by appropriate means. Beneath the reel 1 and with its axis at right angles to the axis of the reel 1, is a small motor 6 carrying a fan 7 adapted to force air through an opening 8 in the top of the housing transversely against reel 1. An opening 9 is provided in one end of housing 5 to admit air, a heater 10 being appropriately mounted in the housing so that the entering air passes over it and is heated before being discharged against the reel 1. By directing the air substantially radially against the reel 1 and the film 71 thereon, a uniform drying of the film is obtained.

The reel 1 includes a pair of circular end plates 11 and 12 which are substantially identical and are joined and maintained in spaced relation as well as against relative rotation by means of the longitudinally extending bars 2. These bars are equally spaced about the periphery of the discs, and may be of any convenient number. For roll film, the bars may be round and fairly closely spaced, as shown. For cut film a modified form of reel may be used, as will be described later.

The end plates 11 and 12 are each provided with an opening, 13 and 14 respectively, to receive a supporting shaft 15. A pulley 16 is secured on shaft 15 near one end thereof, as by means of a pin 17. Pulley 16 carries an offset projecting pin 18 which engages a hole 19 in end plate 11, whereby rotation of the pulley 16 is imparted to the reel 1. Since the cage or reel 1 is detachable from shaft 15, the other plate 12 has a similar hole 20 for receiving pin 18, making it possible to insert shaft 15 from either end of reel 1.

Uprights 3 and 4 are identical flat bars fitting

suitable brackets 22 and 23 secured to the inner surface of the sides of box 5 in any convenient manner, as for example, by welding or riveting. Brackets 22 and 23 are closed at their lower ends, so as to support the uprights 3, 4 in a detachable manner. The uprights are inserted in the brackets and rest on the lower ends. The upper ends of the uprights are provided with half-round openings 24 and 25 in which shaft 15 rests.

Shaft 15 together with reel or drum 1 may be readily lifted from slots 24 and 25, after which uprights 3 and 4 may be removed from their supporting brackets 22, 23. Thus the drier may be readily disassembled so as to occupy less space when desired, as for shipping. Furthermore the shaft 15 may be removed from the reel 1 by a simple axial movement, and inserted in another reel of the same or different type.

The motor 6 is mounted in housing 5 immediately below the reel 1 on a bracket 27 attached to one end 28 of base 5. Motor 6 has a vertical shaft 29 upon which is mounted a pulley 29 surmounted by fan 7. Fan 7 is just below the top 30 of box 5, the top being provided, as before stated, with an opening 7 to permit discharge of air by the fan, and covered by a suitable grill or screen 31.

The other end 32 of base 5 has an opening 9, similar in area to opening 8 and covered by a like screen or grill 33. The heating element 10 is mounted in the base adjacent opening 9. As clearly shown in Figs. 2 and 4, the heater includes a plurality of small diameter coils 34 of resistance wire supported at their opposite ends by asbestos blocks 35 and 36. These asbestos blocks 35 and 36 are respectively supported on the side walls of the base 5 by angle pieces 37, 38.

The motor 6 drives reel 1 by a belt 39, passing about the motor pulley 29 and the reel pulley 16. This belt may be formed of thin coiled wire. To change the direction of the belt travel from a horizontal plane (as required by the motor) to a vertical plane (to suit the film reel), idler pulleys 40 and 41 are rotatably supported in suitable positions on a bar 42 which in turn is supported on brackets 22, as by being welded thereto. Belt 39 also acts to exert a force transversely of shaft 15 in a downward direction, so as to confine the shaft against the half-round slots 24, 25.

The heater 10 and the motor 6 are connected in parallel by leads 43 and 44, both being simultaneously controlled by a switch 45. A conventional cable 46 connects the drier with a suitable source of electric current.

To permit access to the motor and heater, the bottom of the base 5 may be in the form of a cover 47 hinged to the base at 48 and provided

with a suitable thumb screw 49 to hold it shut. Rubber feet 50 are provided on the outside of bottom 47.

The use of the drier is self-evident. Film 11 is wound about the reel 1, being suitably secured to rods 2 by the aid of clips 12. The switch 45 is then closed, energizing the motor 6 and the heater 10. This causes the reel 1 to revolve; at the same time fan 7 forces air through opening 8 against the periphery of the reel, this air being drawn through opening 9 and passing over the heater 10. The film 12 is thus subjected to the stream of heated air, directed in a general radial direction toward the drum periphery and against the exposed emulsion side of the film. The drying operation may be continued as long as necessary.

In case cut film is to be dried, the form of reel shown in Figs. 6 and 7 is preferable. This reel 60 includes end plates 61 and 62, similar to plates 11 and 12, being provided with openings 63, 64 to receive the shaft 15 and driving connection 18. The plates are connected by flat bars 65, spaced approximately the length of pointed hooks 66 formed integrally therewith and adapted to receive one end of the film 61 as shown in Fig. 7. The other end of the film 61 is gripped by a conventional spring clamp 68. Intermediate each pair of hooks 66, each bar 65 has a J slot 69, adapted to receive an elastic band 70 secured to clamp 68. The tension of the band 70 stretches the film 61.

What is claimed is:

1. In a film drier, a housing, uprights extending from the housing, means forming in cooperation with the housing, rests for the uprights from which rests the uprights may be removed, a reel exposed to the atmosphere and having a shaft rotatably supported by the uprights, a motor in the housing for driving the reel, and means for forcing air outwardly of the housing and in a general radial direction to the axis of the reel.

2. In a film drier, a housing, uprights extending from the housing, means forming in cooperation with the housing, rests for the uprights from which rests the uprights may be removed, a shaft rotatably mounted in open slots formed respectively in the uprights, a reel carried by the shaft, means for supporting film on the reel, a motor in the housing, a belt passing into the housing for connecting the motor and the reel and for confining the reel against the wall of the slots, and means for forcing air outwardly of the housing and in a general radial direction to the axis of the reel.

FRANCIS C. FREY.
